[57] **CLAIM**

The ornamental design for a manicure kit, as shown and described.

DESCRIPTION

FIG. 1 is a perspective view of a manicure kit showing my new design with the case in closed position;

FIG. 2 is a perspective view thereof with the case cover opened and the pair of holders with instruments in a flat position;

FIG. 3 is a perspective view thereof with the case cover opened and the pair of holders without instruments in raised position; FIG. 4-7 being the following views of the case for manicure set according to FIG. 1:

FIG. 4 is a bottom plan view thereof;

FIG. 5 is a side elevational view thereof, the opposite side being substantially a mirror image thereof;

FIG. 6 is a front elevational view thereof;

FIG. 7 is a rear elevational view thereof; and

FIG. 8 is a side elevational view thereof with the case cover opened and the pair of holders with instruments in a raised position.
